COIL SYSTEM MORE PARTICULARLY FOR HIGH-FREQUENCY HEATING GENERATORS

Lourens Blok and Gooitzen Zwanenburg, Eindhoven, Netherlands, assignors, by mesne assignments, to North American Philips Company, Inc., New York, N. Y., a corporation of Delaware

Application December 30, 1953, Serial No. 401,324

Claims priority, application Netherlands January 22, 1953

5 Claims. (Cl. 336—62)

This invention relates to a coil system, more particularly for high-frequency heating generators, which comprises a helically wound water-cooled primary coil with a substantially rod-shaped ferromagnetic core and a coupling coil which surrounds the primary coil and consists of a metal strip curved to form a substantially cylindrical shell. The primary coil may form part of the output circuit of an electronic tube generator, and the coupling coil (secondary coil) may be connected to a heater coil (working coil) or concentrator consisting of a single turn, in whose field the article to be heated is disposed.

The impedance constituted by the working coil may have very different values. In order that the full generator power may be given off to the working coil even with the most unfavourable values of said impedance, it is desirable that the secondary coil may be very tightly coupled to the primary coil. This is achieved with the use of the said ferromagnetic core which may, for example, consist of ferrite (cubic mixed crystal material of iron oxide and other metal oxides).

For dissipating the heat evolved by losses in the core it is necessary to employ forced cooling. To this end, the core together with the primary coil—and, as the case may be, the secondary coil—is placed in an oil-filled container. As will be explained later, such forced cooling entails constructional difficulties which are especially related with the positioning of the supply leads to the primary coil. According to the invention these difficulties are overcome, since one of the leads to the primary coil passes through an axial bore of the core and the magnetic circuit formed by the core around said duct is interrupted by a gap.

In order that the invention may be readily carried into effect it will now be described in greater detail with reference to the accompanying drawings representing examples thereof and in which Fig. 1 is a perspective view of one example (for the sake of clearness several parts have been broken away).

Figs. 2 and 3 show in bottom view and in side view respectively, part in section, a second example.

The coil system shown in Fig. 1 comprises a primary coil 1 (shown in axial section) consisting of a helically wound copper tube which is placed in a cylindrical oil-container 3 surrounding the coil co-axially and made from insulating material with low high-frequency losses. The oil container 3 extends with its axis in a vertical direction and is closely surrounded by a metal strip 5 which is curved to form a cylindrical shell and constitutes the secondary coil (coupling coil). At the top the container 3 is provided with a flange 7 to which an insulating cover 8 is screwed in an oil-tight manner.

The ends 9 and 10 of the coil 1 pass vertically through the cover 8 in an oil-tight manner. Disposed within the coil 1 is a co-axial substantially rod-shaped core 11 of ferro-magnetic material having low high-frequency losses, preferably cubic mixed crystal material of iron oxide and other metal oxides (ferrite). The core is supported by three vertical insulating strips or stays 13 (for the

2

sake of clearness one of them has been omitted in the drawing) each consisting of two slotted parts between which the coil 1 is clamped. The stays 13 are partly sunk into vertical slots 15 of the core 11. This core has an axial bore through which passes the supply duct 16 to the lower end of the coil 1. The supply ducts 9 and 10 are connected with a cooling circuit (not shown in the drawing) through which cooling water is supplied to the coil 1. The coupling coil 5 may also be cooled by means of copper cooling tubes 17 soldered thereto. Secured to the ends 19 and 21 of the coupling coil 5 are heavy clamps 23 and 25 for connecting a heater coil (working coil, not shown) of usual construction.

The primary coil 1 acts as an inductance in the oscillatory circuit of a high-frequency heating generator having a power of several kw., which may be of usual construction and is not shown in the drawing. In order to transmit the full high frequency energy to the working coil and the article to be heated in its field a very tight coupling may be required between the primary and the secondary coil 5. This is promoted by providing the core 11 in the coil 1. In order to carry off the heat due to loss of energy in said core, the container 3 is filled with oil which is cooled by the water flowing through the tube 1. Between the coil 1 and the core 11 there are no parts—apart from the stays 13 which cover only a small part of the surface of the coil 11—impeding the flow of oil from the core to the coil and back, which permits intense cooling of the core.

30 The container 3 may consist of a glass tube with a flange 7 cemented thereto and a bottom 27 secured in the same manner. The lead-through of the two current and cooling water supply ducts 9 and 10 through the lid 8, which lead-through is particularly advantageous in connection with oil-tightness, is realized in a practical manner by passing the supply duct 16 to the bottom end of the coil 1 through an axial bore of the core 11. Without further expedients, however, this duct would have a comparatively high self-induction owing to the surrounding ferromagnetic material of the core 11. This self-induction would act as a leakage inductance and consequently weaken the coupling between the primary coil and the secondary coil, which would be prohibitive to the required very tight coupling between the primary coil 1 and the secondary coil. For this reason the core 11 is furnished with a radial saw-cut 29 forming an interruption of the magnetic circuit around the duct 16.

The passing of the duct 16 through a bore of the core 11 not only permits the oil-container to be easily sealed but also yields the advantage of the coupling coil 5 being easily interchangeable. Also in view thereof the coupling coil is disposed at the exterior of the oil-container 3. The easy interchangeability of the coupling coil is of importance in treating work pieces of different size. In this case, for example, the use of a coupling coil axially shorter than that shown in the drawing permits for certain workpieces a better matching of the impedance of the coupling coil to that of the working coil.

60 Figs. 2 and 3 show an example of the invention with a slidably primary coil. Fig. 3 is a part elevational view part sectional view on the line III—III in Fig. 2.

The coil system shown in Figs. 2 and 3 is supported by a horizontal, insulating bed plate 31 constituting the cover of an oil-filled container 33 (Fig. 3). The primary coil 35 and the secondary coil (coupling coil) 37 are secured to the bottom of the plate 31 and immersed in the oil container 33, the adjusting device of the coil system being mainly mounted on top of the bed plate 31. The primary coil 35 together with a capacitor constitute the oscillatory circuit of a high-frequency generator for heating purposes. The circuit capacitor and other component parts of the generator may be disposed adjacent

the coil system at the lower and upper side of the bed plate 31. All these parts may be of usual construction and are consequently not shown in the drawings.

The primary coil 35 is a copper tube, for example 6 mm. thick. It is helically wound and supported by three insulating rods 39, 41, 43, for example made from hard paper and resting against the inner side of the coil. The ends of these rods are secured, for example by means of wedges, in two insulating end plates 45 and 47. Situated between the rods 39, 41, 43 is a substantially cylindrical ferromagnetic core 49 of cubic ferrite material with low losses (mixed crystals of iron oxide and other metal oxides), which material is a poor conductor of electricity. The core 49 is furnished with three long axial slots in which the rods 39, 41, 43 are partly sunk, the diameter of the core being a few mm. smaller than the inside diameter of the helix 35.

The assemblage of helix 35, core 49, supporting rods 39, 41, 43 and bed plates 45, 47 is slideable as a whole over a guide bar 51 of electrically non-conductive material, for example hard paper of unround, for example, rectangular cross-section, which bar passes substantially co-axially through the end plates 45, 47 and through the core 49. To this end, the end plates 45, 47 are provided with mating apertures, the core 49 having a spacious axial bore through which also passes one of the supply ducts (53) of the coil 35.

The coupling coil 37 mainly consists of a curved copper strip which surrounds the coil 35 with a few mm. of intermediate space and is supported by two flat trapezium-shaped insulating supports, 55, 57. The width of the strip—i. e. the axial length of the coupling coil—is approximately equal to the length of the coil 35. The core 49 is approximately 20% longer. Besides constituting the coupling turn 37, the strip also constitutes the double supply duct of this turn. The two ends 59, 61 (Fig. 3) of the strip extend parallel to each other with a few mm. of intermediate space, project obliquely from the oil container 33 and are terminated by heavy clamps 63 and 65. These clamps, together with the edges 59 and 61 of the strip are screwed in an insulating manner to a bracket 67 welded to the container 33.

Through the helix 35 flows water, which is supplied through tubing 69 and 71 and serves to cool the coil as well as the oil surrounding it, this oil cooling, in its turn, the core 49. The heat evolved due to loss of energy in said component parts may thus be safely carried off. In order to cool the coupling coil 37 the copper strip 37, 59, 61 has soldered to it tubes 73 and 75 which may be connected to the cooling water duct, if desired in series with coil 35.

Adjustment of the coupling between the primary coil 35 and the secondary coil 37 is effected by means of a handwheel 77, a roller 79 seated on its shaft and two metal bands 81, 83 adapted to be wound on said roller, this device permitting the primary coil to be axially displaced. For this purpose the band 81 is secured with one end to the roller 79 and passes over a roller 87, freely rotatable in an opening 85 of the plate 31, through the

opening 85 and along the bottom of the plate to the end plate 45. The band 83 similarly passes over a roller 89, through an opening 91 and through slots (not visible in the drawing) of the supports 55, 57 equally to the end plate 45. The two bands are lightly tautened and on operating the hand-wheel 77 one of the bands is unwound from the roller 79, whereas the other band is wound up.

By disposing of the current and cooling water supply duct 53 inside the core 49 the construction-length of the coil system can be minimized, otherwise this duct would project beyond the end plate 47 over a length equal to the distance over which the coil 35 is displaceable.

In order to prevent the supply duct 51 attaining a comparatively high self-induction, which would act as an unwanted leakage inductance owing to the surrounding ferromagnetic material of the core 49, this core is provided with a radial saw-cut 93 which forms an interruption of the magnetic circuit present around the duct 51.

What is claimed is:

- 20 1. A coil system for high frequency heating generators comprising a substantially cylindrical container of electrically insulating material, a helically wound, water-cooled primary coil in said container and extending co-axially with said container, a ferromagnetic core having an axial bore and a radial gap therein, means mounting said ferro-magnetic core axially within said primary coil, a coupling coil secured to the outer surface of said cylindrical container extending co-axially therewith and substantially surrounding said primary coil, a plurality of current and cooling water supply ducts for said primary coil, one of said supply ducts passing through the axial bore of said ferromagnetic core, and the magnetic circuit formed by said core around said one of said supply ducts being interrupted by said radial gap.
- 25 2. A coil system as set forth in claim 1 wherein said container has oil therein and at least said primary coil and said core are disposed therein.
- 30 3. A coil system for high frequency heating generators as claimed in claim 1 wherein said coupling coil includes an arcuate metal strip substantially bent around said container and closely surrounding the primary coil.
- 35 4. A coil system as set forth in claim 1 wherein said primary coil is arranged vertically and the supply ducts pass through the top wall of said container in an oil-tight manner, said top wall being co-axial with said primary coil.
- 40 5. A coil system as set forth in claim 1 wherein said container is substantially cylindrical and constituted of a silica-containing material.
